DESIGN FOR A CHILD'S PURSE

Estelle B. Shevis, Belmont, Maine

Application October 25, 1948, Serial No. 149,285

Term of patent 3½ years

(Cl. D87—3)

To all whom it may concern:

Be it known that I, Estelle B. Shevis, a citizen of the United States, residing at Belmont, in the county of Waldo and State of Maine, have invented a new, original, and ornamental Design for a Child's Purse, of which the following is a specification, reference being had to the accompanying drawing, forming part thereof.

Fig. 1 is a front view, slightly in perspective, of a child's purse embodying my new design; and Fig. 2 is a similar rear view thereof.

The purse is of no substantial thickness.

I claim:

The ornamental design for a child's purse, as shown and described.

ESTELLE B. SHEVIS.
